PREPOSITIONING MOTOR CONTROL

Charles Allan Schurr, Warrensville Heights, and Frank Alan Manners, Cleveland, Ohio, assignors, by mesne assignments, to Square D Company, Detroit, Mich., a corporation of Michigan

Application June 24, 1955, Serial No. 517,752

5 Claims. (Cl. 318—490)

This invention relates to a control system for an electric motor, and more particularly to a control system for automatically predetermining and indicating, between operating periods of the motor, the number of revolutions to be made by the motor during its next subsequent operating period. Although not limited to such use, the invention is described herein as applied to the control of a screw-down motor for a metal rolling mill.

In the operation of many rolling mills, it is necessary to repeatedly vary the spacing of the rolls while reducing a metal piece such as a steel bloom or ingot to a desired size and shape. In so doing the bloom or ingot is passed between the rolls at least once for each spacing. Between the passes, the spacing of the rolls is varied by the screw-down motor. Motor controllers, known as automatic preset screw-down controllers, have been developed which permit one or more complete rolling schedules to be preset thereby rendering the roll spacing for each pass uniform and proper and not a matter of choice by the operator during the reducing operation.

Automatic preset screw-down controllers having differentially driven control elements, such as described and claimed in Wright and Wilcox Patent No. 2,106,965 and in Schurr Patent No. 2,564,284, have been used extensively in the control of various types of rolling mills in several different metal-working industries. The speed and accuracy of these prior controllers is outstanding. There has been a demand, however, for a control system of equal speed and accuracy which permits the operator to select quickly and accurately the next subsequent roll spacing while the metal is between the rolls so that, immediately after the metal leaves the rolls, mere operation of a push button causes the screw-down motor to rotate until the preselected roll spacing is provided for the next successive pass. A preselect system, as distinguished from a preset system, is particularly suitable for mills handling a large number of different sizes of blooms or ingots which would require the pre-setting of an excessively large number of rolling schedules if a preset system were used.

An object of this invention is to provide an improved preselect electric motor control system including means for preselecting, between operating periods of the motor, any desired number of revolutions to be made by the motor during its next subsequent operating period so that, should the operator note the need for a change in his usual procedure, he can institute it between successive starts of the motor.

Another object is to provide an electric motor control system for indicating, and then automatically controlling, the number of revolutions to be made by the motor and including a coarse control cut-out and a fine control cut-out both coupled to the motor through a differential gear.

Another object is to provide an improved motor control system in which, while the motor is stopped, a means which indicates the position of the apparatus driven by the motor can be adjusted to indicate the next desired position of the apparatus and which remains in fixed

2

position during movement, by operation of the motor, of the apparatus to that pre-selected position.

Another object is to provide an improved automatic pre-select screw-down controller.

5 Another object is to provide an improved automatic pre-select screw-down controller in which an indicating means indicates, selectively, the actual roll spacing at the end of an operation of the motor, and, before the next operation of the motor, the desired next subsequent roll spacing to be obtained by such subsequent motor operation, the indicating means being geared to stopping control means which stops the screw-down motor automatically when the desired next subsequent roll spacing is reached.

10 Another object is to provide an improved preselect screw-down controller in which a screw-down motor drives control means which automatically stops the screw-down motor when the rolls are at a preselected spacing and in which a roll-spacing-indicating means and the control means can be preset while the screw-down motor is not operating to indicate and predetermine the next subsequent roll spacing.

15 In accordance with this invention, a screw-down motor is arranged to drive the main driving shaft or gear of a differential gear mechanism through a synchronous-tie system. One of the shafts driven through the differential gearing is coupled to a roll-spacing-indicating means through a second synchronous-tie system and the other of the shafts of the differential gearing drives a fine control or vernier cut-out and a coarse control or main cut-out in fixed speed relation to each other. When the cut-outs reach their respective neutral positions, the screw-down motor is de-energized. To preselect the next roll spacing, the cut-outs are driven a predetermined distance 20 from their neutral positions by a set-up motor geared to the differential shaft which is coupled to the indicating means. Thus when the set-up motor is operated to drive the cut-outs, the indicating means is driven to a position where it indicates the next desired roll spacing. Subsequent operation of the screw-down motor drives the cut-outs until both are returned to their respective neutral positions at which time the screw-down motor stops automatically. During operation of the screw-down motor the differential shaft to the indicating means is self-locked 25 so that the indicating means does not operate and therefore the indicating means gives a true indication of the actual roll spacing when the screw-down motor stops.

Other objects and advantages will become apparent from the following description wherein reference is made to the drawings, in which:

30 Fig. 1 is a schematic layout of a portion of the apparatus showing its relation to a screw-down motor;

Fig. 2 is a schematic front view of the indicating means;

Fig. 3 is a wiring diagram showing the electrical connections for the synchronous-tie machines; and

35 Figs. 4A and 4B together are a complete wiring diagram of the remainder of the control system.

In the wiring diagrams of Fig. 3, 4A, and 4B, some of the switch contacts and their operating windings are shown in convenient physical locations in the diagrams apart from each other and are also shown operatively associated with each other. The switch contacts and windings are referred to by the appropriate reference numeral followed by a letter subscript. In order to simplify the drawing and thereby to make the invention easily understood certain conventional relays and interlocking contacts the use of which in similar control systems is well known have been omitted.

40 Referring principally to Fig. 1, a screw-down motor 10 which may be a series-wound direct current machine having, as shown in Fig. 4A, an armature winding 10a and a series field winding 10f is suitably coupled as by gearing

11 to a screw-down mechanism associated with relatively movable rolls 12 of a metal rolling mill for moving the rolls toward and away from each other. The rotor of a suitable synchronous-tie transmitter 14 is coupled to a shaft 15 driven through gearing 18 by the motor 10. The transmitter 14 drives the rotor of a synchronous-tie receiver 19 having a shaft 20 which drives through gearing 21 a pinion shaft 22 carrying a pinion 24 meshing with a ring or main driving gear 25 of an automobile type differential 26 having differential shafts 28 and 29 drivingly connected to the main driving gear by conventional differential gears. The motor 10 is thus in fixed driving relation with the rolls 12 and the differential 26, and the differential 26 may be mounted in any convenient location with respect to the motor 10.

The shaft 28 of the differential 26 is coupled to the rotor of a transmitter 30 of a synchronous-tie system, including a receiver 31 mounted in a housing 32 of a roll-position-indicating means or indicator 34. The synchronous-tie system 30-31 permits the indicator 34 to be mounted at any convenient location with respect to the differential 26, for example, adjacent to master switches to be described.

The indicator 34 may comprise gearing 35 which couples the rotor of the receiver 31 to a shaft 36 carrying at its forward end portion a fine or vernier pointer 38 associated with a graduated dial 39 (Fig. 2). A coarse pointer 40 associated with a graduated dial 41 is driven by gearing 42 and 43 from the shaft 36. In the illustrative example, the maximum roll spacing is assumed to be fifteen inches and the gearing is selected so that the pointer 40 makes one revolution while the rolls are moving the full fifteen inches. One inch increments of the fifteen inch spacing are marked on the dial 41. The ratio of the gearing 42 and 43 is such that the pointer 38 rotates 15 times faster than the pointer 40 and thus the dial 39 is graduated to show tenths and hundredths of an inch of roll spacing. A rearward extension of the shaft 36 has a knob that may be used for adjustment of the pointers 38 and 40 and preferably the stator of the receiver 31 is rotatable in the housing 34 to permit accurate calibration of the indicator with respect to the spacing of the rolls 12. After calibration, the frame of the receiver 31 is locked in position by suitable means (not shown).

Keyed at an intermediate portion of the shaft 28 is a worm wheel 44 meshing with a worm 45 secured to the shaft of a suitable pre-selecting or set-up motor 46 which is shown in Fig. 4A as a shunt wound direct current machine having an armature winding 46a and a shunt field winding 46f.

Rigidly secured to the outer end portion of the shaft 29 is an arm 48a (Fig. 4B) of a fine control device or vernier cut-out 48 and keyed at an intermediate portion of the shaft 29 is a worm 49 meshing with a worm wheel 50 on a shaft 51 coupled to an arm 52a (Fig. 4B) of a coarse control device or main cut-out 52. Although the cut-outs 48 and 52 may be of any suitable type and may be cam operated, they are shown in Fig. 4B as of the face plate type. The various contact segments of the cut-outs 48 and 52 are identified by the appropriate reference numeral followed by a letter subscript and will be further referred to in the description of operation.

The ratio of the worm 49 and wheel 50 may be any suitable value, but for greatest accuracy preferably is relatively high, as for example 60 to 1 so that six degrees rotation of the arm 52a corresponds to one revolution of the arm 48a. Further in the illustrative example, the gearing between the arm 48a and the rolls 12 is such that one inch of roll travel corresponds to two revolutions of the arm 48a and thus twelve degrees of rotation of the arm 52a corresponds to one inch of roll travel.

When the pinion 24 is driving the ring gear 25, the shaft 29 rotates but the shaft 28 does not since it is locked by the worm 44 and wheel 45. On the other hand, when the set-up motor 46 is operated to drive the shaft 28 and

10 the pinion 24 is not rotating, the shaft 29 rotates at the same speed as the shaft 28 but in the opposite direction due to action of the differential 26. Thus, in the illustrative example, if the set-up motor is operated to drive the indicator to show a one inch movement of the rolls 12, the arm 48a makes two revolutions and the arm 52a rotates 12 degrees from its initial position. If the one inch movement of the rolls is to space the rolls 12 further apart, the arms 48a and 52a rotate in one direction from their neutral position, whereas if the roll movement is to space the rolls 12 closer together, the arms 48a and 52a rotate in the opposite direction.

Referring now to Fig. 3, when a knife switch 54 is closed, primary windings of the synchronous-tie machines 14 and 19 are connected to a suitable source of alternating current indicated by conductors 55. The rotor windings of the machines 14 and 19 are permanently connected together as are those of the synchronous-tie machines 30 and 31. Upon closure of a master switch shown as a push button 56, the primary windings of the synchronous-tie machines 30 and 31 are connected to the source 55 and an operating winding 58w of an electromagnetic relay 58 is energized causing the relay 58 to move to its operated position. The relay 58 serves as an interlock between the alternating current portion of the control system shown in Fig. 3 and the direct current portion shown in Fig. 4B and hence the contacts of the relay 58 are shown in Fig. 4B. As will become apparent, should the alternating current source 55 fail while the system is operating automatically, consequent deenergization of the relay 58 causes the motor 10 to stop thereby to maintain synchronism between the rolls 12 and the cut-outs 48 and 52 and the indicator 34.

Referring now to Fig. 4A, the motors 10 and 46 are arranged to be supplied from a suitable direct current source indicated by the supply conductors 59 and 60. The armature winding 10a of the screw-down motor 10 is arranged to be connected for driving the rolls 12 upwardly upon closure of a normally open, two-pole, electromagnetic contactor 61 and for driving the rolls 12 downwardly upon closure of a normally-open, two-pole electromagnetic contactor 62. An operating winding 64w of a suitable spring-applied, electromagnetically released brake (not shown) for the motor 10 may be connected in series with the motor. An acceleration and plugging controlling resistor 65 also in series with the motor 10 has portions arranged to be by-passed by normally-open, single-pole, electromagnetic contactors 66, 67, and 68, respectively, the contactor 66 serving as a plugging contactor during non-automatic operation of the motor 10. Slowdown of the motor 10 prior to stopping is effected by an armature shunt circuit including a resistor 69 which is arranged to be connected across the armature 10a upon closure of a normally open, single pole, electromagnetic contactor 70, normally open, single-pole electromagnetic contactors 71 and 72 being provided to vary the effective value of the resistor 69. A normally open, single-pole, electromagnetic contactor 73 serves to connect the motor 10 to the supply conductor 60.

The set-up motor 46 which may be a fractional horse-power machine is arranged to be reversibly connected to the conductors 59 and 60 through a permanent resistor 74 by selective operation of a normally open, double-pole, electromagnetic forward or up contactor 75 and a normally open, double-pole, electromagnetic reverse or down contactor 76. Slowdown of the motor 46 prior to stopping is effected by an armature shunt circuit including a resistor 78 arranged to be connected across the armature 46a by a normally closed, single-pole, electromagnetic contactor 79. Final slowdown of the motor 46 just prior to stopping is accomplished by short-circuiting the armature 46a by closure of a normally open, single pole, electromagnetic contactor 80.

Operation of the set-up motor 46 is controlled by a two-position reversing master switch 81 having contacts

81a through 81d. In the off position of the master switch 81, the contact 81c is closed and completes an energizing circuit for an operating winding 80w of the contactor 80 from the conductor 59 to the conductor 60. The contact 81c is open in all other positions of the master switch 81 and the contacts 81a, 81b, and 81d are open in the off position and are closed in those other positions where closure is indicated by crosses aligned with the contacts. In the up positions of the master switch 81, the contact 81a is closed and completes an energizing circuit for an operating winding 75w of the up contactor 75 and in the down positions the contact 81d is closed and completes an energizing circuit for a winding 76w of the down contactor 76. The contactor 79 which controls the armature shunt circuit through the resistor 78 remains closed in both first positions and opens when the master switch 81 reaches either one of its second positions since closure of the contact 81b completes an energizing circuit for an operating winding 79w of the contactor 79. Thus by operation of the master switch 81 the motor 46 may be operated at two different speeds in either direction and stops quickly when the off point is reached because the contactor 80 then closes to short-circuit the armature winding 46a.

The screw-down motor 10 may be operated non-automatically by means of a multi-position, reversing, master switch 82 (Fig. 4B) having contacts 82a through 82f. The contacts 82b and 82f are closed in the off position and crosses aligned with the contacts indicate the closed condition of the contacts 82a through 82e in the other positions. When the master switch 82 is in any of its up positions, an energizing circuit is completed through the contact 82d for an operating winding 61w of the up contactor 61, and when the master switch 82 is in any of its down positions, an energizing circuit is completed through the contact 82e for an operating winding 62w of the down contactor 62. The contact 82c is closed whenever the master switch 82 is in one of its operating positions and completes an energizing circuit for an operating winding 73w of the contactor 73. When the master switch 82 is in either of its first positions all of the resistor 65 is in series with the motor 10. Upon movement of the master switch 82 to either of its second positions, an energizing circuit is completed through the contact 82b for an operating winding 66w of the plugging contactor 66 which may also be controlled by a plugging relay (not shown) in a well known manner. Upon movement of the master switch 82 to either of its third positions, an energizing circuit is completed through the contact 82a and a normally closed contact 84a of a control relay 84 for an operating winding 67w of the contactor 67. After a time delay of an acceleration relay (not shown), an energizing circuit is also completed from the contact 84a through a normally closed contact 85a of a control relay 85 to an operating winding 68w of the contactor 68.

It is thus seen that the master switch 82 provides a means to control the motor 10 manually, that is, non-automatically, so as to move the rolls 12 any desired distance in opposite directions selectively at any of three different speeds. This manual operation of the motor 10 can be effected with alternating current power available or not. Preferably the master switches 81 and 82 are arranged adjacent to each other and to the indicator 34.

Before the motor 10 can be operated automatically, the system must be synchronized with the indicator 34 set to indicate the exact distance between the rolls 12 and with the cut-outs 48 and 52 at their respective neutral positions. This is preferably accomplished by removing power from the synchronous-tie machines 30 and 31, operating the motor 10 by means of the master switch 82 until the rolls 12 are a predetermined distance apart, and then operating the set-up motor 46 until the arms 48a and 52a are in their respective neutral positions. The knob on the indicator shaft 36 is then used to set the pointers 38 and 40 so that they indicate the predetermined

roll spacing. Power is then re-applied to the machines 30 and 31 and to the relay winding 58a. There is a tendency for the receiver 31 to rotate slightly when power is re-applied to thus disturb the setting of the pointers. If this rotation occurs, the stator of the receiver 31 may be turned slightly in the housing 32 to compensate for the change in setting and then again locked in position.

In describing automatic operation of the system, it will be assumed that the system has been synchronized as just described, that the gear ratios are as previously given for the illustrative example, that the rolls 12 are exactly five inches apart, and that it is desired to move the rolls 12 toward each other 1 1/4 inches so that they become 3 1/4 inches apart. Since the system is synchronized, the pointers 38 and 40 of the indicator 34 stand so that 5.00 inches is read from the dials 39 and 41. The master switch 82 must be in its off position during automatic operation. The push button 56 is closed so that the synchronous-tie machines 30 and 31 are energized and the relay 58 is in its operated position.

The set-up motor 46 is now started in the down direction by manipulation of the master switch 81 and drives the shaft 28 of the differential 26 until the pointers 38 and 40 indicate the desired spacing of 3 1/4 inches. The master switch 81 is then returned to the off position and the set-up motor 46 stops. By the locking action of the worm 44 and worm wheel 45, the pointers 38 and 40 are held in the selected position during subsequent operation of the screw-down motor 10. Because of the assumed gear ratios previously mentioned, this operation of the set-up motor 46 has driven the vernier cut-out arm 48a from its neutral position 3 1/2 revolutions in a clock-wise direction (Fig. 4B) and the main cut-out arm 52a from its neutral position twenty-one degrees in a clock-wise direction. As soon as the contact arm 52a moved from its neutral position, a contact bridge 52b on the arm 52a bridged a main contact ring 52m and a down contact segment 52d. A circuit was thereby completed from the supply conductor 59 through the master switch contact 82f, the contact ring 52m, the contact bridge 52b, the contact segment 52d, and an operating winding 86w of a down relay 86 to the supply conductor 60. Consequently a normally closed contact 86b of the relay 86 is now open and isolates an up segment 48u of the vernier cut-out 48 from the circuit and normally open contacts 86a and 86c of the relay 86 are now closed and complete a by-pass circuit to be described around the cut-out 48 so that the position of the contact arm 48a is of no consequence at this time.

When it is desired to operate the screw-down motor 10, a master switch shown as a push button 88 is closed and completes an energizing circuit for an operating winding 89w of a relay 89 from the conductor 59 through the contacts 82f and 58b, the push button 88, and the winding 89w to the conductor 60. A normally open contact 89a of the relay 89 closes immediately and causes energization of an operating winding 84w of the control relay 84. Consequent closure of a normally open contact 84d of the relay 84 completes an energizing circuit for the operating winding 62w of the down contactor 62 from the supply conductor 59 through the contact 84d, the contacts 86a and 86c of the relay 86, a contact 58e of the relay 58, and the winding 62w to the conductor 60. At the same time, closure of a normally open contact 84c of the relay 84 causes energization of the operating winding 73w of the contactor 73. The resultant closure of the contactors 62 and 73 causes the motor 10 to run in the down direction. The plugging portion of the resistor 65 is excluded because the contactor 66 is closed as a result of energization of the winding 66w through the contact 82b. An energizing circuit is also completed for the windings 67w and 68w through the contacts 84d, 86a, 58a, and 84b causing sequential closure of the contactors 67 and 68 to permit the motor 10 to reach its maximum speed, closing of the contactor 68.

being delayed in a well known manner as previously mentioned. Closure of a contact 62a on the contactor 62 completes with the contact 89a a bypass circuit around the push button 88 which may now be released. If desired, the contacts 89a may be delayed in opening so that the push button 88 may be released as soon as the contacts 89a close.

Operation of the motor 10 in the down direction moves the rolls 12 toward each other and causes the shaft 29 of the differential 26 to drive the main cut-out arm 52a counter-clockwise towards its neutral position. Before the arm 52a reaches its neutral position, the contact bridge 52b engages a contact segment 52p thereby to complete an energizing circuit for an operating winding 91w of a relay 91 provided a knife switch 92 is in its upper position. If the knife switch 92 were in its lower position, the relay 91 would be operated sooner by engagement of the contact bridge 52b with a contact segment 52n. Operation of the relay 91 causes closure of a contact 91a which completes an energizing circuit for an operating winding 85w of the relay 85. Consequent opening of the contact 85a of the relay 85 causes opening of the contactor 68, and closure of a contact 85b of the relay 85 causes energization of the operating winding 78w of the contactor 70 which completes the armature shunt circuit for the motor 10 causing the motor 10 to operate at a slower speed. Thus the knife switch 92 permits the starting point for slowdown of the motor 10 to be adjusted.

Because of the exemplary gear ratios previously mentioned, when the arm 52a is three degrees from its neutral position, a contact bridge 48b on the arm 48a of the vernier rheostat 48 engages a contact segment 48d and completes a circuit between the segment 48d and the contact ring 48m. When the arm 52a is 2 1/4 degrees from its neutral position, the contact bridge 52b leaves the contact segment 52d which deenergizes the relay 86 causing its contacts 86a and 86c to open thereby opening the by-pass circuit around the vernier rheostat 48 and one of the circuits to the winding 62w. Since the contact bridge 48b has left the contact segment 48u, re-closure of the contacts 86b is of no effect.

Engagement of the contact bridge 48b with the contact segment 48d completes a circuit from the conductor 59 through the contact 84d, the contact ring 48m, the contact bridge 48b, the contact segment 48d, normally closed contacts 94b of an up relay 94, and the contacts 58e through the winding 62w to the conductor 60. The contactor 62 thus remains in its closed position and the motor 10 continues to operate in the down direction driving the contact arm 48a counter-clockwise toward its neutral position. Before the contact arm 48a reaches its neutral position, a contact bridge 48c on the arm 48a completes a circuit from a contact segment 48p to a contact segment 48r. This completes a circuit from the conductor 59 through the contacts 82f and 58b and the operating winding 72w of the armature shunt contactor 72 to the conductor 60. The contactor 72 thereupon closes to reduce the effective value of the resistor 69 in the armature shunt circuit for the motor 10. The motor 10 consequently slows down and continues to run at a slower speed. A short time later the contact bridge 48b engages a contact segment 48n to complete a circuit from the contact ring 48m through the brush 48b and the segment 48n to the operating winding 71w of the armature shunt contactor 71 which thereupon closes to reduce further the effective value of the resistor 69 in the armature shunt circuit for the motor 10.

The speed of the motor 10 is now very slow. When the arm 48a reaches its neutral position the contact bridge 48b leaves the segment 48d causing opening of the contactor 62. This deenergizes the motor 10 and causes the friction brake operated by the winding 64w to set and stop the motor 10. The motor 10 has now driven the

rolls 12 toward each other so that they are now exactly 3 1/4 inches apart as shown by the indicator 34.

Opening of the contactor 62 caused opening of the contacts 62a in the holding circuit for the time relay 89. After a time interval, the relay 89 opens its contacts 89a causing deenergization of the relays 84 and 85 and the contactor 70. Opening of the relay 84 causes deenergization of the contactors 67 and 73.

If it should now be desired to separate the rolls, the master switch 81 is operated to cause the set-up motor 46 to operate in the up direction. This moves the pointers 38 and 40 on the indicator 34 to indicate the desired wider roll spacing and at the same time moves the arms 48a and 52a a comparable distance counter-clockwise. When the push button 88 is now closed, circuits similar to those previously described are completed except that the contact segment 52u is first effective and the contact segment 48u later becomes effective instead of the contact segments 48d and 52d. The up control relay 94 having, in addition to its normally closed contacts 94b, normally open contacts 94a and 94c operates during separation of the rolls instead of the down relay 86, and the up contactor 61 closes to cause the motor 10 to operate in the up direction. An energizing circuit for the winding 61w is completed around the cutout 43 through the contacts 84d, 94a, 94c, and 58d. The contacts 61a instead of the contacts 62a serve to complete the circuit around the push button 88 while the motor 10 is operating in the up direction.

It is thus seen that while the motor 10 is stopped, the set-up motor 46 can be operated to preselect the direction of operation and the number of revolutions to be made by the motor 10 during its next subsequent operating period. Although a rheostatic control system has been shown for controlling the acceleration and speed of the screw-down motor, it will be understood that a variable voltage system can be used if desired. If a variable voltage system is used, the cut-outs 48 and 52 preferably would control contactors or relays associated with the supply generator field to control the direction and speed of the screw-down motor.

Having thus described our invention, we claim:

1. An electric motor and control system combination for controlling and indicating the next stopping position of a member drivable by a motor to different selected positions, successively, and comprising a motor, a member connected to the motor so as to be driven thereby to different positions, a control device including a movable settable means having a neutral position and movable, in one direction, while the motor is not operating, to different preselected set positions spaced from said neutral position, connecting means operatively connecting said movable settable means to said motor for driving said movable settable means from the position preselected while the motor was not operating, in an opposite direction toward said neutral position upon the next succeeding operation of said motor, said control device also including means rendered operative when said movable settable means reaches said neutral position to stop said motor, whereby the position to which said member is to be moved by said motor during the next operating period of the motor is preselected prior to the said next operating period, an indicating means, coupling means operatively coupling said indicating means to said movable settable means so that said indicating means is driven in fixed relation to said movable settable means, when the movable settable means is driven in said one direction, to a position which indicates the final predetermined position to which the member will have been driven upon completion of said next operating period of the motor, and means rendering said coupling means inoperative when said motor is driving said movable settable means in said opposite direction, toward its neutral position, and concurrently is driving said member toward said final predetermined position.
2. A control system and motor combination in accord-

ance with claim 1 characterized in that said motor drives said movable settable means through a differential gear having its main driving gear connected to the motor, and said indicating means is coupled to one of the output shafts of the differential gear, and said movable settable means is coupled to the other of the output shafts of the differential gear.

3. A control system and motor combination in accordance with claim 1 characterized in that said movable settable means is movable selectively in opposite directions from said neutral position, said motor is reversible, and means associated with said control device determines the direction of operation of said motor during its next period of operation depending upon the direction said movable means is moved from said neutral position.

4. A control system and motor combination in accordance with claim 1 characterized in that said control device

includes means for controlling the speed of said motor and rendered operative to reduce the speed of said motor when said movable means nears said neutral position.

5. A control system and motor combination in accordance with claim 4 characterized in that said speed controlling means includes one control means for controlling said motor during high speed operation of said motor, another control means for controlling said motor during slow speed operation of said motor, and means for transferring from said one control means to the other after said motor has slowed down.
